UNITED STATES PATENT OFFICE.

JOHN A. LAMONT, OF CHICAGO, ILLINOIS, ASSIGNOR TO AMERICAN STEEL FOUNDRIES, OF CHICAGO, ILLINOIS, A CORPORATION OF NEW JERSEY.

JOURNAL BOX.

Application filed April 28, 1921. Serial No. 465,268.

To all whom it may concern:

Be it known that I, JOHN A. LAMONT, a citizen of the United States, residing at Chicago, in the county of Cook and State 5 of Illinois, have invented certain new and useful Improvements in Journal Boxes, of which the following is a specification.

This invention relates to a railway car truck journal box.

10 One object of the invention is to provide a simple, journal box having its parts arranged in a manner to accommodate associated equalizing mechanism in an improved manner.

15 Another object is to provide an improved journal box having parts whereby it may move guidably in a truck side frame and still permit the passage of parts therethrough in connection with the equalization of loads.

20 These and other objects are accomplished by means of the arrangement disclosed on the accompanying sheet of drawings in which—

25 Figure 1 is a fragmentary vertical longitudinal sectional view of a truck side frame and associated parts including my improved journal box.

30 Figure 2 is a fragmentary horizontal longitudinal sectional view of the same side frame showing its cooperative action with my journal box;

35 Figure 3 is an end elevation of the journal box; and,

40 Figure 4 is a side elevation of said journal box.

The various novel features of my invention will be apparent from the following description and drawings and will be par-

45 ticularly pointed out in the appended claims.

By referring to the figures of the drawings it will be noted that I have disclosed my invention in connection with a side frame 10 forming part of a six-wheel truck, said side frame having an intermediate pocket 11 for a middle journal box 12, said intermediate pocket 11 being formed between side walls 13 which preferably are 50 provided with wear plates 14.

This journal box includes a main central body portion for the reception of a journal 55 and also includes outwardly and upwardly extending wing portions each having a pair of spaced side walls 16, which

at their outer ends are joined by an end wall 17. Accordingly wide open ended vertically arranged passageways or spaces are formed at each side of the journal box between the main body portion, end walls 17 60 and the side walls 16. These vertical end walls 17 and the outer edges of the side walls 16 cooperate with the pocket walls 13 or more particularly in this present case, with the wear plates 14 whereby the journal 65 box is guided in its relative vertical movements with respect to the side frame.

The top wall 18 of the journal box is provided with a concave bearing portion 19 for the reception of a rocking portion 20 70 of an equalizing beam 21 upon which springs 22 are mounted. Mounted over the springs is a spring cap or yoke 23 in the form of an inverted U having depending arms 24 which extend freely downwardly 75 through the vertical open-ended passageways or spaces 25 formed by the walls 16 and 17 of the journal box. Operatively connected to the lower ends of the arms 24 are equalizing levers 26 from which loads 80 are transmitted through the arms 24 of cap 23, through the springs 22, equalizing beam 21 to the top of the journal box. The journal box is provided with the hollow wings for the purpose of freely accommodating 85 the arms 24 of the spring cap 23 and permitting movements of the latter thereby providing sufficient clearance for all parts and preventing any interference in the operative movements. A combination of the 90 load equalizing arrangement described in this paragraph is claimed in a copending application, Serial No. 465,941, filed April 30, 1921.

It is my intention to cover all modifications of the invention falling within the spirit and scope of the following claims.

I claim:

1. A railway car truck journal box comprising a journal receiving portion and hollow wide open-ended wings having portions cooperating to guide vertical movements of said journal box, the openings through the hollow wings permitting the passage of load equalizing parts. 100

2. A railway car truck journal box comprising a journal receiving portion and hollow wide open-ended wings extending outwardly therefrom for guiding said box in its vertical movements and for permitting 110

the passage of equalizing parts there-through.

3. A railway car truck journal box comprising a journal receiving portion, the top 5 of which takes the spring pressure, spaced walls extending outwardly from said portion for cooperating to guide the journal box in its vertical movements and to permit the passage of load equalizing parts there- 10 between.

4. A railway car truck journal box comprising a journal receiving portion, spaced side walls extending outwardly therefrom and terminating in end walls connecting 15 said side walls whereby the journal box will be guided in its vertical movements and pro-

vides wide open ended openings through which associated parts may extend.

5. A railway car truck integrally formed journal box comprising a box portion for 20 receiving a journal and the top of which takes the spring pressure, spaced side walls extending upwardly and outwardly from said box portion and end walls connecting said side walls for cooperating to guide the 25 journal box in its vertical movements, said spaced walls, end walls and box portion forming walls of openings through which associated parts may extend.

Signed at Chicago, Illinois, this 18th day 30 of April, 1921.

JOHN A. LAMONT.
